UNITED STATES PATENT OFFICE.

OSWALD E. WINGER, OF FREEPORT, ILLINOIS.

GRINDING-MILL.

SPECIFICATION forming part of Letters Patent No. 227,465, dated May 11, 1880.

Application filed June 23, 1879.

To all whom it may concern:

Be it known that I, OSWALD E. WINGER, of Freeport, Stephenson county, State of Illinois, have invented new and useful Improvements 5 in Grinding-Mills, of which the following is a full description, reference being had to the accompanying drawings, of which there are three sheets, in which—

- Figure 1 is a top view; Fig. 2, a side view; 10 Fig. 3, an edge view; Fig. 4, an inside view of one-half of the case; Fig. 5, a plan of the fixed rings; Figs. 6 and 7, details of the hub E; Fig. 8, a plan of the movable grinding-ring; Fig. 9, an edge view of the same. Fig. 15 10 is a section taken at line *x* of Fig. 4. Fig. 11 is a side elevation with one side of the case and fixed ring connected therewith removed. Fig. 12 is a detail. Fig. 13 is a vertical cross-section.
- 20 This invention relates to that class of grinding-mills which are designed to be operated through the action of a windmill, giving to the movable grinding-ring an intermittent rotary movement; and it consists in the devices 25 which are hereinafter claimed and described.

In the drawings, A represents the case, which consists of two parts, B B, which are alike and can be cast from the same pattern. The upper part of each half B of the case 30 forms one-half of a hopper, C, and the edges of the two halves of the case do not come together except at the top. *a* are lugs on the inside of B B. D D are grinding-rings, one on the inside of each half of the case. They are 35 cast separate from the case, and are held in place by lugs *b* on the periphery, which fit between the lugs *a*, or some of them. These rings are not complete, a space, *s*, being left for the passage of the grain, as shown at Figs. 5 and 40 13. *c* is a bolt which passes through both parts of the case. E is a hub loose on the bolt *c*. It is provided with two flanges, one on each side, which extend under the stationary grinding-rings D D. *d* are lugs on the periphery of 45 the hub E.

F is a loose grinding-ring. It has three recesses, *e*, in its inner edge, with which three of the lugs *d* engage. The remaining lugs *d* serve to carry in grain from the hopper. The hub E 50 and loose ring F rotate together. *f* are ratchet-teeth on the outer edge of the loose grinding-

ring F. G is a ring which fits loosely over and around the loose grinding-ring F. In an enlargement, *g*, on one side is pivoted a pawl, *h*. Behind this pawl *h* there is a spring, *i*, 55 which holds the pawl out so that it will engage with the teeth *f*. *j* are cog-teeth on a portion of the periphery of G. *k* is an arm on the ring G. It is provided with a series of holes, and to it the reciprocating rod of a 60 windmill can be connected.

l is a pinion on a shaft which has its bearings in the two walls *m m*, which extend across the hopper, the pinion being between these two walls and covered by the flanges on the 65 upper edges thereof. The teeth *j* on G engage with the pinion *l*. The shaft *n*, on which this pinion is placed, extends into the hopper C on each side, and is provided with one or more arms, *p*, which serve the purpose of agitating the 70 grain in the hopper, which grain passes through the passages *s*, and through the open space in the stationary grinding-rings, part going between the movable grinder F and one of the stationary rings, and part between the movable 75 ring and the other stationary ring, there being two passages from the hopper leading to opposite sides of the central movable grinding-ring F. The grain falls upon the periphery of the hub E, which keeps it between the rings. 80 *r* are ears on the case to receive bolts for securing the mill to any suitable frame-work.

The loose grinding-ring F is allowed to move laterally on the lugs *d* on the hub E, thereby avoiding all cramping, which is liable to occur 85 when the grinding-rings are rigidly fastened to a shaft. The several parts are held together by the single bolt *c*, which can be tightened or loosened to make the mill grind fine or coarse.

The operation is as follows: The reciprocating rod of a windmill or other power is to be attached to the lever *k* in any suitable manner, but so that the movement of such rod will give to the ring G a vibratory movement; then, through the pawl *h*, which engages with the 90 ratchet-teeth *f* on the movable grinding-ring F, when the lever-ring G is moved downward, or in the direction of the arrow of Fig. 2, the pawl engages with the teeth on the yielding ring and communicates motion to it. On the 95 upward or return movement of the lever-ring the grinding-ring remains stationary. Thus

the action of the mill gives to such movable grinding-ring an intermittent rotary motion. At the same time the teeth *j* will, through the pinion *l*, give a vibratory rotary motion to the 5 agitators *p* in the hopper, preventing the grain from clogging.

I do not limit the use of my improvements to grinding-mills which are used in connection with a windmill.

10 The grinding-ring *F* can be operated by a continuous rotary motion through a pinion and gear-cogs on the periphery of the loose ring, instead of ratchet-teeth, and the agitators *p* might be operated by means of gear-cogs on 15 the loose grinding-ring *F*.

What I claim as new, and desire to secure by Letters Patent, is as follows:

1. The combination of the ring *G*, provided with a pawl, *h*, and teeth *j*, with the pinion *l*, 20 agitators *p*, and movable grinding-ring *F*, substantially as and for the purposes specified.

2. The hub *E*, provided with lugs *d* on its periphery and having flanges extending under the stationary grinding-rings *D D*, in combination with a movable grinding-ring, *F*, having recesses *c* on its inner edge, substantially as and for the purposes specified. 25

3. The case *A*, consisting of two like parts, *B B*, each provided with lugs *a* on the inside, in combination with two stationary detachable grinding-rings, *D D*, each provided with lugs *b* and central fastening and pivot bolt, *C*, substantially as and for the purposes set forth. 30

4. The hub *E* and loosely-attached grinding-ring *F*, having free lateral movement between 35 the stationary grinding-rings *D D*, and in combination therewith, substantially as set forth.

OSWALD E. WINGER.
